OPERATING MECHANISM FOR
TYPEWRITERSGeorg Baier, Altenberg, near Nuremberg,
GermanyApplication April 18, 1935, Serial No. 17,078
In Germany May 2, 1934

13 Claims. (Cl. 197—25)

This invention relates to operating mechanisms for typewriters of the kind comprising a type-carrier that moves in straight direction, that is perpendicularly to the platen, and is driven from the key-lever by means of a double system of crank-levers, said system of crank-levers including a connecting member in the form of a weighted lever.

As compared with known type-operating mechanisms in which the driving members are positioned in the rear of the guides for the type-heads, thus necessitating a prolongation in the construction of the typewriter, the operating mechanism which forms part of my present invention is characterized essentially by the fact, that the type-carrier is provided with an under guide-rod mounted displaceably in bearing-blocks and that the thrust and motion members which are interconnected by said weighted lever and acting on said type-carrier are mounted above and below the rear path of motion of said guide-rod.

By so constructing the operating mechanism I attain more favorable driving conditions resulting in a minimum effort for depressing the key-lever and at the same time in noiseless operation of said mechanism. In addition to this, the dimensions of the typewriter may be considerably shortened, which is due to the fact that the entire operating mechanism, that is the thrust and motion-members for the type-carriers are positioned very closely to the type-heads and within the space required for the motion of said guide-rod.

According to my invention, furthermore, the typewriter may be easily constructed with only two types on a type-head and accordingly only with a single lift of the carriage or platen because my new operating mechanism will immediately permit to employ side by side a greater number of keys and types as required in typewriters of this kind, without, however, increasing the width of the latter.

My invention may therefore be successfully employed especially in connection with small travelling or portable typewriters, as well as with larger standard typewriters for regular office work.

My invention further comprises a special construction of the type-operating mechanism in such a manner, that the crank-lever which imparts motion to the upper thrust-member upon being actuated by the key-lever is provided with a straight driving slot having an outward circular extension with its center at the point of rotation of the lever, and that said driving slot en-

gages with a driving pivot of a double-armed transmission-lever connected with the key-lever, motion of said transmission-lever being so impeded, preferably by abutting against its bearing-block, that said motion and thrust-members will follow the action of the weighted lever inserted therebetween to be able to act by free swinging motion.

From this construction follows the advantage, that said motion and thrust-members are released from the action of the key-lever in depressed condition of the latter, with the result that said members will operate solely by action of said weighted lever.

Furthermore, a uniform impact of the types against the platen is ensured by this construction and, in addition, a simplified arrangement for the feed of the carriage by means of the so-called universal rail, which is operated from said crank-lever by the intermediary of the additional swingable operating lever, proper mode of operation being effected and ensured especially by the fact, that my new operating mechanism permits to place said crank-lever and said operating lever one in the rear of the other within the same plane between common bearing members.

By this specific construction of the type-operating mechanism the mode of operating the types will be still further improved as a whole, both with respect to the bearings for the motion members as well as with respect to simplicity of construction and assembling of the several parts of the mechanism, and at the same time reliably ensuring proper operation of all parts of the mechanism.

In the accompanying drawings I have represented two forms of construction of my new type-operating mechanism in Figs. 1, 2 and 3 and in Figs. 4, 5, 6 and 7, respectively. Of said first form of construction Fig. 1 shows the type-operating mechanism in inoperative condition, while Fig. 2 represents the operative condition thereof and Fig. 3 is a partial top-view of a typewriter equipped with the new type-operating mechanism. Said second form of construction comprises an improved special arrangement of the several parts, of which Fig. 4 shows said mechanism in inoperative condition, Fig. 5 in operative condition; Fig. 6 is a partial top-view of the typewriter showing the bearing-bridge for the under part of the type-operating mechanism, while Fig. 7 shows some details of the bearing and driving members co-operating with said bearing-bridge.

In both forms of construction shown in the drawings the type-carrier 1 is provided with a

rearward extension 3 and with an under guide-rod 2 which in inoperative position of the type-operating mechanism projects in rearward direction into the space which serves for the reception of the operating parts of the mechanism, said guide-rod 2 being mounted movably in a bearing member 12.

A thrust-rod 4 is hinged onto the extension 3 of the type-carrier 1 by means of a pivot 6, 10 said thrust-rod 4 being further hinged to the one end of a double-armed lever 5 the other end of the latter being hinged to one end of a crank-lever 7; the latter is swingably mounted on a bearing member 8, which may be adjusted by 15 means of the screws 9 to vary the swinging motion of said crank-lever. The other end of said crank-lever is preferably provided with a ball 10 engaging with a recess 11 in the bearing member 12 to be fixed thereby.

20 Pivotal connection of the double-armed lever 5 or upper thrust-rod with the under crank-lever 13 to which motion is imparted from the key-lever 16 by the intermediary of the transmission-lever 15 is completed by the weighted lever 14. 25 Said under crank-lever 13 is under action of a retracting spring 18 engaging with the upper curved arm of the former and being swingably mounted between two bearings 17 mounted on a transverse bridge. The transmission lever 15 interposed between the crank-lever 13 and the 30 key-lever 16 is mounted in a bearing 21.

The upwardly directed arms of the crank-levers 13 and 7 are both of two-part construction, the guide-rod 2 moving through the free space between both parts of said arms of the crank-levers 13 and 7, all as shown in Fig. 1 of the drawings.

In the construction shown in Figs. 1 and 2 the crank-lever 13 is in permanent operative engagement with the transmission-lever 15 which is 40 movably coupled with the key-lever 16. The transmission-lever 15, moreover, is positioned in front of the crank-lever 13 and the bearing for the former is mounted on the same transverse bridge together with the bearings 17 and 8 for the crank-levers 13 and 7.

Noiseless operation of the type-operating mechanism upon return motion into its inoperative position shown in Fig. 1 is ensured by pads 19 and 20 of soft material, such as felt, rubber, 50 leather or the like, said pads forming a stop or abutment for the return motion of the weighted lever 14 and the key-lever 16.

In the construction shown in Figs. 4, 5, 6 and 7 the part 13 of the type-operating mechanism is 55 no more in permanent operative engagement with the transmission-lever 15, the transmission lever 15 coupled with the key-lever in this case engaging from the rear with the crank-lever 13. Moreover, the latter is equipped with a straight slot 24 merging into a circular extension as shown at 25, Figs. 4 and 5, the center-point of said circular extension coinciding with the center of rotation 27 of the crank-lever 13. A pivot 26 engages with said slot 24, said pivot 26 being mounted at the one end of a double-armed transmission-lever 15 swinging about the bearing-pivot 21, while the other end of said lever 15 is in connection with the key-lever 16.

The transmission-lever 15 is stopped in its 70 swinging motion, for instance by abutting against its bearing 21, in such a manner that the operating or thrust-members 13, 14 as well as 4, 5 are released near the end-position of the depressed key-lever and enabled to follow the motion of the weighted lever 14 forming part of

the operating members of the mechanism and to freely act onto the type carrier 3. The crank-lever 13 is equipped near its bearing point 27 with a nose or pawl 23 and acted upon by a retracting spring 18. Said pawl 23 acts onto the round 5 or pivotally constructed head-piece 22 of an actuating lever 20 which is likewise positioned between the two bearing members 17 on the transverse bridge 18, and mounted swingably round the pivot 20 so as to abut with its free end against a yielding pad 29 which may consist of leather, rubber or the like. The free end of said actuating lever 20 engages from underneath with the universal rail 30 hinged to the bearing-beam 12, said universal rail 30 actuating the feed of the carriage 15 subsequent to each depression of the key-lever. Between the bearing members 17 on the transverse bridge 18, besides the crank-lever 13 and the actuating lever 20 which are positioned in the same plane one in the rear of the other, 20 there is also mounted the bearing-block 8 carrying the crank-lever 7 for connection with the thrust-members 5, 4. The bearing-block 8 is mounted movably on the axle 28 to permit adjustment of the swinging motion, said axle 28 carrying also the actuating lever 20. Said bearing block 8 is supported by two adjusting screws 9 acting against the base of the bearing, the alternate adjustment of said screws permitting to vary the position of said bearing block 8 and 30 therewith to move or swing the bearing-head that carries the crank-lever somewhat towards the left or towards the right. From this arrangement of the several parts of the type-operating mechanism follows the possibility of adjusting 35 the stroke of the types with respect to the platen.

In the above mentioned second form of construction of the type-operating mechanism according to Figs. 4, 5, 6 and 7 the operation of the several parts, as seen from the position of 40 rest (Fig. 4) will be as follows:

Upon depression of the key-lever 16 the transmission-lever 15 will be rotated, the swinging motion of the latter being limited by abutment against the bearing-block 21, thus likewise swinging 45 the crank-lever 13 upward by the intermediary of the pivot 26 engaging with the slot 24 in said lever, said crank-lever 13 stretching the thrust-rods 5, 4 by way of the weighted lever 14, said thrust-rods 5, 4 pushing forward the type-head 1 against the platen. Before completion of 50 this motion the pivot 26 on the transmission-lever 15 is disengaged from the slot 24 in the crank-lever 13 and now comes in engagement with the circular extension 25 of said slot, thus releasing 55 the type-operating members from the key-lever 16 and causing said members to be actuated by the momentum of the weighted lever 14 to follow the motion of the latter striking the type against the platen, as shown in Fig. 5.

The pawl 23 on the crank-lever 13, upon rotation of the latter, acts onto the head-piece 22 of the actuating lever 20, thus swinging the free end of the latter upward round the point of rotation 28 and lifting the rail 30 to initiate feeding 65 motion for the carriage. Upon completion of the imprint the type-operating members will again return at once into inoperative position by action of the retracting spring 18 on the crank-lever 13, the return motion being further assisted by the weight of the feed-rail 30 acting onto the lever 20, the head-piece 22 of the latter abutting against the pawl 23 on the crank-lever 13. The type-operating members will thus return very 70 75

quickly into inoperative position. Obviously, the construction of my new type-operating mechanism permits to operate the typewriter at a greater speed than had heretofore been possible.

5 In Fig. 7 I have separately shown the parts of my new type-operating mechanism that are placed, besides the crank-lever 13, between the two bearing-members 17 on the transverse bridge 19, that is the bearing-head 8 and the actuating lever 20.

10 On the transverse bridge 19, as may be seen especially from Fig. 6, there is mounted in radial arrangement a proper number of bearing-members 17, the operating members for the several 15 types being mounted side by side between said bearing members in the manner described hereinabove.

I claim:

20 1. Operating mechanism for typewriters, said mechanism comprising a type-carrier, guide-means for guiding said type-carrier in a direction perpendicular to the platen of a typewriter, a key-lever, a system of thrust and motion members including a weighted lever interposed between said 25 type-carrier and said key-lever, said guide-means including a guide-rod mounted displaceably in bearing-elements, a crank-lever mounted swingably on a bearing-block positioned below said 30 guide-rod, adjusting means for said bearing-block to vary the swing of said crank-lever, and operative connections between said thrust-members and the one end of said crank-lever, the other end of said crank-lever engaging with one 35 of said bearing-elements, bearings for said system of thrust and motion members and said crank-lever, said bearings being positioned below said guide-rod, said system of thrust and motion members being mounted partly above and partly below said guide-rod.

40 2. Operating mechanism for typewriters, said mechanism comprising a type-carrier, guide-means for guiding said type-carrier in a direction perpendicular to the platen of a typewriter, a key-lever, a system of thrust and motion members 45 including a weighted lever interposed between said type-carrier and said key-lever, said guide-means including a guide-rod mounted displaceably in bearing-elements, a crank-lever mounted swingably on a bearing-block positioned below 50 said guide-rod, adjusting means for said bearing-block to vary the swing of said crank-lever, operative connections between said thrust-members and the one end of said crank-lever, the other end of said crank-lever engaging with one of said 55 bearing-elements, bearings for said system of thrust and motion members and said crank-lever, said bearings being positioned below said guide-rod, said system of thrust and motion members being mounted partly above and partly below 60 said guide-rod, said mechanism including a retracting spring for said system of thrust and motion members.

65 3. Operating mechanism for typewriters, said mechanism comprising a type-carrier, guide-means for guiding said type-carrier in a direction perpendicular to the platen of a typewriter, a key-lever, a system of thrust and motion members including a weighted lever interposed between 70 said type-carrier and said key-lever, said guide-means including a guide-rod mounted displaceably in bearing-elements, a crank-lever mounted swingably on a bearing-block positioned below said guide-rod, adjusting means for said bearing-block to vary the swing of said crank-lever, said system of thrust and motion members including an actuating lever mounted with said 75

lever, operative connections between said thrust-members and the one end of said crank-lever, the other end of said crank-lever engaging with one of said bearing-elements, bearings for said system of thrust and motion members and said 5 crank-lever, said bearings being positioned below said guide-rod, said system of thrust and motion members being mounted partly above and partly below said guide-rod, said crank-lever being of two-part construction providing a space there-between, said guide-rod passing through said space.

4. Operating mechanism for typewriters, said mechanism comprising a type-carrier, guide-means for guiding said type-carrier in a direction perpendicular to the platen of a typewriter, a key-lever, a system of thrust and motion members including a weighted lever interposed between 15 said type-carrier and said key-lever, said guide-means including a guide-rod mounted displaceably in bearing-elements, bearings for said 20 thrust-members, and a thrust lever operatively connected to said thrust and motion members and the carriage feed mechanism, said bearings and said thrust lever being mounted on a common 25 bearing-bridge positioned between said guide-rod and said key-lever, said system of thrust and motion members including said weighted lever being as a whole positioned partly above and partly below said guide-rod. 30

5. Operating mechanism for typewriters, said mechanism comprising a type-carrier, a key-lever, a system of levers interposed between said key-lever and said type-carrier, said system of 35 levers including a weighted lever, a guide-rod for said type-carrier, said guide-rod being displaceably mounted in bearing-elements, said system of levers and said weighted lever being mounted as a whole partly above and partly below said guide-rod, a pawl on one of said levers, 40 an actuating lever, and a universal rail operatively engaged with said actuating lever for feeding the carriage of the typewriter, said pawl engaging with the head-piece of said actuating lever whereby said rail is under control of said pawl. 45

6. Operating mechanism for typewriters, said mechanism comprising a type-carrier, a key-lever, a system of levers interposed between said key-lever and said type-carrier, said system of levers including a weighted lever, a guide-rod for said 50 type-carrier, said guide-rod being displaceably mounted in bearing elements, said system of levers and said weighted lever being mounted as a whole partly above and partly below said guide-rod, said system of levers further including 55 a thrust lever, a pawl on said thrust lever, a feed rail for the carriage of the typewriter, and a lever for actuating said feed rail, said pawl engaging with the carriage feed rail lever whereby said rail is under the control of said pawl. 60

7. Operating mechanism for typewriters, said mechanism comprising a type-carrier, guide-means for guiding said type-carrier in a direction perpendicular to the platen of a typewriter, a key-lever, a system of thrust and motion members including a weighted lever interposed between 65 said type-carrier and said key-lever, said guide-means including a guide-rod mounted displaceably in bearing-elements, a crank-lever mounted swingably on a bearing-block positioned below said guide-rod, adjusting means for said bearing-block to vary the swing of said crank-lever, said system of thrust and motion members including an actuating lever mounted with said 70

crank-lever in a common plane, one in the rear of the other, between two bearing members.

8. Operating mechanism for typewriters, said mechanism comprising a type-carrier, guide-means for guiding said type-carrier in a direction perpendicular to the platen of a typewriter, a key-lever, a system of thrust and motion members including a weighted lever interposed between said type-carrier and said key-lever, said

5 10. guide-means including a guide-rod mounted displaceably in bearing-elements, a double-armed actuating lever mounted with one of said thrust and motion members in a common plane, one in the rear of the other, between two bearing members.

15 9. Operating mechanism for typewriters, said 20 mechanism comprising a type-carrier, guide-means for guiding said type-carrier in a direction perpendicular to the platen of a typewriter, a key-lever, a system of thrust and motion members including a weighted lever interposed between

25 said type-carrier and said key-lever, said guide-means including a guide-rod mounted displaceably in bearing-elements, a double-armed actuating lever mounted with one of said thrust and motion members in a common plane, one in the rear of the other, between two bearing members, a crank-lever mounted on an adjustable bearing-block, said bearing-block being likewise positioned between the aforesaid two bearing members, said system of thrust and motion members as well as

30 35 said weighted lever and said actuating lever as a whole being mounted partly above and partly below said guide-rod.

10. Operating mechanism for typewriters, said mechanism comprising a type-carrier, guide-

40 means for guiding said type-carrier in a direction perpendicular to the platen of a typewriter, a key-lever, a system of thrust and motion members including a weighted lever interposed between said type-carrier and said key-lever, said 45 guide-means including a guide-rod mounted displaceably in bearing-elements, a double-armed actuating lever mounted with one of said thrust and motion members in a common plane, one in the rear of the other, between two bearing mem-

50 bers, a crank-lever mounted on an adjustable bearing-block, said bearing-block being likewise positioned between the aforesaid two bearing

members, said double-armed actuating lever and said crank-lever being mounted to swing about a common axle on the aforesaid bearing-block.

11. Operating mechanism for typewriters, said mechanism comprising a type carrier, a key lever, 5 a system of levers interposed between said key lever and said type carrier, said system of levers including a weighted lever, and a guide rod for said type carrier, said guide rod being displaceably mounted in bearing elements, said system of 10 levers and said weighted lever being compactly arranged above and below said guide rod and being mounted on supports arranged below said guide rod.

12. Operating mechanism for typewriters, said 15 mechanism comprising a type carrier, guide means for guiding said type carrier in a direction perpendicular to the platen of a typewriter, a key lever, and a system of thrust and motion members including a weighted lever interposed 20 between said type carrier and said key lever, said guide means including a guide rod mounted displaceably in bearing elements, said system of of thrust and motion members as well as said weighted lever being compactly arranged above 25 and below said guide rod and mounted on supports arranged below said guide rod.

13. Operating mechanism for typewriters, said mechanism comprising a type carrier, a key lever, 30 a system of levers interposed between said key lever and said type carrier, said system of levers including a weighted lever, a guide rod for said type carrier, said guide rod being displaceably mounted in bearing elements, said system of levers and said weighted lever being mounted as a 35 whole partly above and partly below said guide rod, said system of levers including a thrust lever in operative connection with said key lever, said thrust lever having a straight slot and an outwardly directed circular extension of said slot, 40 the center point of said circular extension coinciding with the point of rotation of said thrust lever, a double armed transmission lever cooperating with said key lever and engaging with said slot, and an abutment for said transmission lever 45 adapted to release said system of levers and said type carrier from said key lever in depressed condition thereof, whereby said system of levers and said type carrier may follow the free swinging motion of said weighted lever. 50

GEORG BAIER.
